UNITED STATES PATENT OFFICE

2,486,863

ULTRA HIGH FREQUENCY SIGNAL-TRANSLATING STAGE

Donald H. Mitchell, Chicago, Ill., assignor to
Motorola, Inc., a corporation of Illinois

Application November 22, 1944, Serial No. 564,675

5 Claims. (Cl. 250—36)

1

This invention relates to ultra-high-frequency signal-translating stages and, while it is of general application, it is particularly adapted to be applied to a balanced push-pull ultra-high-frequency oscillator. The invention also relates to a balanced tuning unit particularly suitable for use in such a stage or oscillator.

Heretofore there have been proposed numerous ultra-high-frequency oscillators and other signal-translating stages embodying as the tuning means therefor a resonant transmission line, either of the concentric or parallel-conductor types, usually short circuited at the remote end. The parallel-conductor type has the advantages of simplicity and relatively lower cost, ease of tuning, and higher characteristic impedance. In general, the tuning of such lines has been effected by an adjustable sliding contact member which short circuits the line and varies its effective length, it being well known that such a line is resonant at a frequency of which the length of the line corresponds to one-quarter wave length.

While such arrangements theoretically are very satisfactory, in practice, at frequencies of 100 megacycles upwards, it becomes difficult to obtain the desired power output due to a number of factors principally involving the mechanical design of the apparatus. For example, such a structure generally involves a certain number of brackets, supports, and other structural elements of irregular shapes having points, corners, etc., which radiate and dissipate a considerable quantity of power. Further there are generally included a number of lead-conductors of considerable length from the resonant line to its associated vacuum tube, which conductors also radiate and dissipate power and introduce impedance and admittance at portions of the circuit where these parameters are undesired. For example, it is desirable to concentrate all of the reactive impedance of the stage in the tuned circuit.

It is an object of the invention, therefore, to provide a new and improved ultra-high-frequency signal-translating stage including a tuning means of the resonant-line type by which one or more of the above mentioned disadvantages of the arrangements of the prior art may be avoided.

It is another object of the invention to provide a new and improved ultra-high-frequency signal-translating stage including tuning means of the resonant-line type by means of which radiation and dissipation from portions of the structure and circuit, where they are ineffective, are reduced to a minimum.

It is another object of the invention to pro-

2

vide a new and improved resonant-line tuning unit for use in an ultra-high-frequency signal-translating stage which realizes the advantageous characteristics described.

5 In accordance with the invention, an ultra-high-frequency signal-translating stage comprises electron discharge means including a plurality of electrodes, a two-conductor resonant line having an open end, the conductors of the open end terminating individually closely adjacent a pair of the electrodes and being electrically connected thereto. The stage also includes means for tuning the line comprising opposed condenser stator plates individually carried by the open-end conductors and a cooperative condenser plate common to the stator plates and adjustable relative thereto.

Further in accordance with the invention, an ultra-high-frequency stage of the type described 20 comprises a push-pull oscillator comprising a pair of electron-discharge devices each having an anode, a cathode and a control electrode, the open-end conductors of the line terminating individually closely adjacent to, and being connected to, a corresponding electrode preferably the anode, of each of the pair of devices. The oscillator also includes regenerative coupling between the respective anodes and control electrodes of the devices to produce sustained oscillations.

Further in accordance with the invention there is provided a balanced ultra-high-frequency tuning unit suitable for use in the signal-translating stage of the invention and comprising a two-conductor resonant line having an open end, two opposed groups of condenser stator plates, each of the groups comprising at least two plates and being carried by one of the open-end conductors and at least two cooperating condenser plates common to the opposed stator plates and adjustable symmetrically relative thereto in a plane parallel to a plane of the stator plates. The cooperating plates are also individually adjustable transversely to such plane to balance the unit and are adapted to be connected to a point of zero high-frequency potential.

For a better understanding of the invention, together with other and further objects thereof, reference is had to the following description taken in connection with the accompanying drawings while its scope will be pointed out in the appended claims.

Referring now to the drawings, Fig. 1a is a perspective view of an ultra-high-frequency signal translating stage of the oscillator type em-

bodying the invention; Fig. 1b is a detail bottom view showing the connections of a resonant line to the electron discharge devices; Fig. 2 is a schematic circuit diagram of the oscillator of Fig. 1; while Figs. 3a and 3b are plan and end views, respectively, of an alternative form of balanced resonant-line tuning unit.

Referring now to Fig. 1a of the drawings, there is shown a balanced ultra-high-frequency signal-translating stage of the oscillator type comprising electron-discharge means including a plurality of electrodes and a balanced ultra-high-frequency resonant-line tuning unit therefor. Specifically, this stage comprises a balanced ultra-high-frequency push-pull oscillator including a pair of electron-discharge devices 10 and 11, shown in dotted lines for the sake of clarity. Each of the devices 10 and 11 is of the conventional triode type including an anode, a cathode and a control electrode or grid.

The ultra-high-frequency tuning unit comprises a two-conductor resonant line having one open end and preferably made up of two parallel cylindrical conductors 12 and 13, respectively. The conductors 12 and 13 at their open end terminate individually closely adjacent a pair of the electrodes of the electron-discharge means, specifically adjacent a corresponding electrode of each of said pair of devices, such as their anodes, and are electrically connected thereto. This is shown in Fig. 1b in which the conductors 12 and 13 are secured to a base 14 by upsetting or overturning their ends at 12a, 13a, respectively, at the same time engaging connection lugs 15 and 16, respectively, connected to the immediately adjacent connection lugs 10a and 11a associated with the tubes 10 and 11 or their sockets, as the case may be. The remote end of the line comprising conductors 12 and 13 is short-circuited by a pair of opposed clamping bars 17 adjustably secured to the conductors by means such as a bolt 17a. The electrical midpoint 17b of one of the shorting bars 17 is connected to a source of space current B+ for the tubes 10 and 11 through a radio-frequency choke 18a and is connected to ground through a radio frequency by-pass condenser 18b.

The ultra-high-frequency tuning unit also includes means for tuning the resonant line comprising opposed condenser stator plates individually carried by the open-end conductors near their open ends and a cooperating condenser plate common to the stator plates and adjustable symmetrically relative thereto. Specifically, the opposed stator plates comprise two opposed groups, each of the groups comprising at least two plates and preferably comprising U-shaped plates 20 and 21 folded closely about the open ends of the cylindrical conductors 12 and 13, respectively, to form two pairs of opposed stator plates 20a, 20b and 21a, 21b, respectively. The tuning means also includes two cooperating condenser plates common to the opposed stator plates. These cooperating plates are preferably in the form of a pair of parallel approximately figure-eight condenser rotor plates 22, 23 mounted on an insulated shaft or sleeve 24 and disposed between the pairs of plates 20a, 20b and 21a, 21b and between the plates of each pair. The plates 22 and 23 are rotatable or otherwise adjustable symmetrically relative to the stator plates 20a, 20b and 21a, 21b in planes parallel to the planes of the stator plates; that is, the axis of rotation of the shaft 24 is normal to the planes of the condenser stator plates. The rotor plates

22, 23 are also individually adjustable transversely to the planes of the stator plates, that is, parallel to their axes of rotation, to balance the tuning unit. This transverse adjustment of the rotor plates 22 and 23 may be effected in any desired manner, preferably by bending or otherwise deforming one or both of the plates.

The ultra-high-frequency oscillator of Fig. 1a also includes a second two-conductor open-end resonant line, the open-end conductors being coupled individually to the cathodes of the devices 10 and 11. This second line is similar to the first line and the elements are given the same reference numerals with the added subscript 1 so that its description need not be repeated. The coupling from the open-end conductors 12₁ and 13₁ to the cathodes of the devices 10 and 11, respectively, is effected by means of the insulated cathode heating connections 10b, 11b which pass through the tubular conductors 12₁ and 13₁, respectively, and beneath the base plate 14 to the lugs of the tubes 10 and 11, respectively, or of the sockets of such tubes, as shown in Fig. 1b. One of each of the terminals 10b, 11b is connected to a terminal 17a₁ on the shorting bar 17a which, as indicated, is also connected to ground while the other of each of the pairs of conductors 10b, 11b is connected to a source of cathode heating voltage indicated at A+, through a radio-frequency choke coil 19.

The condenser rotor plates 22, 23 and 22₁, 23₁ mounted on the common shaft 24 are adapted to be adjusted by any suitable mechanism such as the worm gear 31 and worm 32, which may be actuated manually or may be motor driven.

The oscillator thus includes the resonant line 12, 13 between the anodes of the devices 10 and 11 and ground and the resonant line 12₁, 13₁ between their control grids and ground, the resonant line, comprising conductors 12₁ and 13₁, being common to the anode-cathode circuits and the grid-cathode circuits of the devices 10 and 11. The oscillator also includes an output loop or turn 25 having arms lying closely adjacent the conductors 12₁ and 13₁ and the shorting bars 17; for deriving ultra-high-frequency oscillations from the line comprising the conductors 12₁ and 13₁. A shield 33, shown in dotted lines for the sake of clarity, is disposed between the resonant lines 12, 13 and 12₁, 13₁ substantially to eliminate coupling between these lines.

The operation of the balanced push-pull ultra-high-frequency oscillator described above will be best understood by reference to the simplified circuit diagram of Fig. 2 in which corresponding elements are given the same reference characters. The basic oscillator circuit is essentially a conventional one but utilizing resonant-line tuning units in place of the more usual tuning circuits comprising lumped inductance and capacitance. However, the circuit is somewhat unconventional in that the tuning means is divided between the anode and cathode circuits of the oscillator tubes, the line comprising the conductors 12 and 13 being connected in the anode circuit and that comprising the conductors 12₁ and 13₁ being connected in the cathode circuit. As indicated, the midpoint of the line comprising conductors 12₁, 13₁ remote from the devices 10 and 11 is grounded. Similarly, the midpoint of the line comprising conductors 12, 13 remote from the anodes of the devices 10 and 11 is grounded through a by-pass condenser 18b. Each of the conductors 12, 13 and 12₁, 13₁ is approximately one-quarter wave length long. However, the ef-

fective length of the anode line 12, 13, that is the length to the shorting bars 17, 17, is substantially less than that of the line 12₁, 13₁, this difference being introduced to compensate for the difference in the inherent anode-cathode capacitances of tubes 10 and 11.

The grids of the device 10 and 11 are directly interconnected and, since the potentials induced on the grids of the devices 10 and 11 by their respective anodes through the anode-grid capacitances 10c, 11c, respectively, are substantially equal in magnitude and opposite in phase, due to the opposite phase of their anode potentials, these potentials tend to neutralize each other leaving the grids floating at substantially zero ultra-high-frequency potential. The resulting oscillator circuit is substantially conventional, that is, the grids of each of the tubes being at substantially zero or ground potential and the anodes and cathodes fluctuating with respect thereto in opposite phase. While the exact nature of the oscillation-sustaining feedback is not fully understood, it is believed that the regenerative coupling required to generate sustained oscillations is due to the resonant line, comprising conductors 12₁ and 13₁, which comprises resonant self-impedances common to the grid-cathode and anode-cathode circuits of the tubes 10 and 11. The output loop 25 coupled to the cathode resonant line 12₁, 13₁, is connected by way of a coaxial transmission line 27, or other suitable means, to the utilization circuit.

The tuning means for the lines 12, 13 and 12₁, 13₁, electrically are substantially conventional as illustrated in Fig. 2. However, the use of the resonant line conductors themselves as the supporting members for the condenser stator plates 20, 21 and 20₁, 21₁ and the location of the resonant line conductors 12, 13 immediately adjacent the anode connection lugs 10a, 11a, of the tubes 10, 11, respectively, reduces to a minimum the amount of undesired radiation and dissipation from irregular supporting brackets and elements and from conductor leads of substantial length. At the same time, the tuning system is completely symmetrical so that the rotor plates 22, 23 and 22₁, 23₁ may, if desired, be connected to a point of zero ultra-high-frequency potential, such as ground. The auxiliary trimmer condensers 29, 30, connected in parallel with the tuning condensers 20—23 and 20₁—23₁, aid in aligning the resonant frequencies of the two resonant lines. The system may be adjusted to balance by lateral bending or adjustment of one or more of the rotor plates 22, 23 and 22₁, 23₁ to adjust the capacitance curves of the two portions of the figure-8 condenser rotor plates and thus maintain a balance over the tuning range of the oscillator circuit. In general, such an adjustment can be made by means of two or more rotor plates disposed between fixed stator plates while the use of a single rotor plate between each pair of adjacent stator plates is ineffective since adjustment of the rotor plate nearer to one stator plate to increase the capacitance with respect thereto simultaneously and correspondingly decreases the capacitance of the rotor plate to the other stator plate.

While the operation of the oscillator has been described on the basis that the control grids of tubes 10 and 11 are maintained at substantially zero ultra-high-frequency potential, it will be understood that any suitable unidirectional or low-frequency control potential may be applied to the grids as through a radio-frequency choke

coil 28. In one embodiment the grids were maintained at a slightly negative unidirectional potential to block oscillations and were pulse-modulated by positive pulses in order periodically to develop strong sustained oscillations and thus generate a series of pulses of ultra-high-frequency oscillations.

While it will be appreciated that the design constants of the ultra-high-frequency oscillator 10 described may be varied within wide limits in accordance with the particular installation requirements, however, there follow by way of example only the essential circuit constants of one embodiment of the invention:

- 15 Vacuum tubes 10, 11, type 3A5/2
- Conductors 12, 13—copper tubing, $\frac{5}{32}$ inch diameter, O. D., 3 inches in length
- Shorting bars 17, $\frac{3}{8}$ inch from remote ends of conductors 12, 13
- 20 Conductors 12₁, 13₁—copper tubing, $\frac{5}{32}$ inch diameter, O. D., $3\frac{3}{4}$ inches in length
- Shorting bar 17₁, $\frac{1}{8}$ inch from remote ends of conductors 12₁, 13₁
- 25 Condensers 20—23 and 20₁—23₁, max. capacitance 25 mmf, min. capacitance 10 mmf.
- Trimmer condenser 29, 2.5 mmf.
- Trimmer condenser 30, 5.0 mmf.
- By-pass condenser 186, 1000 mmf.
- Tuning range, 200—250 mc.

30 In Figs. 3a and 3b there is represented a modified form of the invention in which two simultaneously tunable resonant lines are arranged with their open-end conductors in opposition and in axial alignment. In this case a U-shaped resonant line 40 having open-end conductors 40a and 40b is arranged in opposed relation to a U-shaped resonant line 41 having open end conductors 41a and 41b. Supported from the open ends of the conductors 40a, 40b are opposed groups of condenser stator plates 40c and 40d, respectively. Similarly supported from the open ends of conductors 41a, 41b are the opposed groups of condenser stator plates 41c and 41d, respectively. Cooperating with the stator plates 40c, 40d are two pairs of rotor plates 42 and 43, each pair being disposed between adjacent ones of the stator plates. Similarly pairs of rotor plates 44 and 45 are disposed between and cooperate with the opposed stator plates 41c and 41d, each pair being arranged between a pair of adjacent stator plates. The rotor plates 42, 43, 44 and 45 are mounted on a common shaft 46 journaled in the short-circuited ends of the resonant lines 40, 41 and 40e and 41e, respectively, and adapted to be actuated by any suitable means such as a tuning knob 47. As indicated in Fig. 3b, the configuration of the stator plates and rotor plates is substantially the same as that of corresponding elements of the structure of Fig. 1a. The principles of operation of the balanced resonant-line tuning unit of Fig. 3b are entirely similar to those explained above with reference to Fig. 1a and need not be repeated. This construction has some electrical advantage in that there is minimum of coupling between the two resonant lines so that the requirement for shielding of these lines is minimized. Its use in some installations is limited by the increased space requirements in the direction of the axis of the opposed resonant lines.

While there have been described what are at present considered to be the preferred embodiments of the invention, it will be apparent to those skilled in the art that various changes and

modifications may be made therein without departing from the spirit or scope of the invention.

I claim:

1. A balanced ultra-high-frequency push-pull oscillator comprising, a pair of electron discharge devices each having an anode, cathode and control electrode, a first two-conductor resonant line having an open end, the conductors of said open end terminating individually closely adjacent the anodes of said pair of devices and being electrically connected thereto, a second two-conductor open-end resonant line the conductors of said open end being coupled individually to the cathodes of said pair of devices, means for tuning each of said lines comprising opposed condenser stator plates individually carried by said open-end conductors and a cooperating condenser plate common to said stator plates and adjustable symmetrically relative thereto, and means for simultaneously moving said condenser plates of said first and second resonant lines for simultaneously tuning said first and second resonant lines.
2. A balanced ultra-high-frequency push-pull oscillator comprising, a pair of electron discharge devices each having an anode, cathode and control electrode, a first two-conductor resonant line having an open end, the conductors of said open end terminating individually closely adjacent the anodes of said pair of devices and being electrically connected thereto, a second two-conductor open-end resonant line the conductors of said open end being coupled individually to the cathodes of said pair of devices, means for tuning each of said lines comprising opposed condenser stator plates individually carried by said open-end conductors and a cooperative condenser plate common to said stator plates and adjustable symmetrically relative thereto, means for simultaneously moving said condenser plates of said first and second resonant lines for simultaneously tuning said first and second resonant lines, a regenerative coupling between the anodes and control electrodes of said devices to produce sustained oscillations, and an output loop coupled to one of said lines.

3. A balanced ultra-high-frequency tuning unit comprising, an open-end resonant line comprising two parallel cylindrical conductors, two opposed pairs of condenser stator plates, each pair comprising a U-shaped plate folded around an open end of one of said conductors and supported thereby, at least two cooperating condenser plates common to said opposed stator plates and adjustable symmetrically relative thereto in a plane parallel to a plane of said stator plates, said co-

operating plates being also individually adjustable transversely to said plane to balance said unit and being adapted to be connected to a point of zero high-frequency potential.

4. A balanced ultra-high-frequency tuning unit comprising, an open-end resonant line comprising two parallel cylindrical conductors, two opposed pairs of condenser stator plates, each pair comprising a U-shaped plate folded around an open end of one of said conductors, a pair of cooperating condenser plates disposed between said stator plates and adjustable symmetrically relative thereto in a plane parallel to a plane of said stator plates, said cooperating plates being also individually adjustable transversely to said plane to balance said unit and being adapted to be connected to a point of zero high-frequency potential.
5. A balanced ultra-high-frequency tuning unit comprising, an open-end resonant line comprising two parallel cylindrical conductors, two opposed pairs of condenser stator plates, each pair comprising a U-shaped plate folded around an open end of one of said conductors, a pair of approximately figure-8 condenser rotor plates disposed between said opposed stator plates and adjustable symmetrically relative thereto in a plane parallel to a plane of said stator plates, said cooperating plates being also individually adjustable transversely to said plane to balance said unit and being adapted to be connected to a point of zero high-frequency potential.
